CLAIM

The ornamental design for a vertical support brace bracket panel for holding tubular objects, as shown and described.

DESCRIPTION

FIG. 1 is a left side, front and bottom perspective view of a vertical support brace bracket for holding tubular objects;

FIGS. 2 and 3 are respectively front and rear elevational views thereof;

FIGS. 4 and 5 are respectively left and rear elevational views thereof;

FIGS. 6 and 7 are top and bottom plan view thereof. The broken line showing of clamping arms is for illustrative purposes only and forms no part of the claimed design.

FIG. 1

FIG. 2

FIG. 3

FIG. 4

FIG. 5

FIG. 6

FIG. 7
